COLLAPSIBLE CRADLE BLOTTER

Frieda Straus, Chicago, Ill.

Application May 10, 1943, Serial No. 486,331

1 Claim. (Cl. 120—24)

This invention relates to a novel and unique collapsible cradle blotter.

One of the essential objects of this invention is to provide a cradle blotter which is inexpensive in its construction, and is readily collapsible for convenience in shipment and storage and the like, and is also readily extendible into cradle form for convenient use.

Another object of this invention is to arrange and shape the construction so that the collapsible cradle blotter can be easily and economically manufactured, which is preferably accomplished by providing a lower cradle part along with an upper handle part, as well as bendable brace means therebetween, all provided from one strip or one piece of sheet-like material.

A further object of this invention is to provide and to arrange such a form of economical cradle blotter which is adapted to be made from one strip or sheet of fibrous material, so that it may be made of cardboard, and have several extra sheets of blotting material provided under the lower cradle part, as indicated in Figs. 1 to 6 of the drawing, and it may likewise be made wholly from one strip or sheet of highly absorbent fibrous material, as blotting material, as indicated in Figs. 7 and 8.

These and various other objects and advantages are attained with this invention, as will become apparent from the following description, taken in connection with the accompanying drawing wherein the invention is shown in two of the preferred forms, it being evident that other arrangements and forms of construction may be resorted to for carrying out the objects and purposes of this invention.

In the drawing:

Fig. 1 is a plan view illustrating a sheet of material from which this collapsible cradle blotter is made, in its preferred form, including several extra blotting sheets provided on the lower section.

Fig. 2 is a top plan view of this form, showing the lower section under the top section with its end secured thereto, and the two sections collapsed together.

Fig. 3 is a side view of this form collapsed.

Fig. 4 is a top plan view of this form with the sections placed apart in the operative cradle form.

Fig. 5 is a sectional view thereof, taken on line 5—5 of Fig. 4.

Fig. 6 is a sectional view, taken on line 6—6 of Fig. 5.

Fig. 7 is a perspective view, showing the in-

vention in an operative position and as embodied in a slightly modified form which consists of one piece or sheet of blotting material.

Fig. 8 is a sectional view thereof, taken on line 8—8 of Fig. 7.

This collapsible cradle blotter is preferably made from one strip or piece of sheet-like material which is arranged to comprise the lower blotting part or cradle section 10 and also the 10 upper handle part or section 11 being integral at one end, and said sections being folded or doubled over and have the originally separated ends secured together. This is preferably accomplished by providing an end portion 12 of one 15 section with adhesive means 13, as is best shown in Figs. 1 and 5 by the lip 12 provided on the lower section 10, and thus securing said portion 12 onto the end part of section 11.

One of these sections is provided with brace 20 means thereon, which includes one or more portions bendable into engagement with the other sections; and this is preferably done by providing side portions or wings 14 integral on the upper section 11 and extending outward beyond 25 the lower section 10, said wings being defined by forming indentations or score lines 15 on section 11, so that these wings or portions 14 can be readily bent on these lines inward and downward into engagement with the lower section 10 30 and form brace means therebetween and retain them in the operative cradle shape. Said wings thus also form part of the handle to be engaged by the hand, and they are readily retracted to place them with the sections in the collapsed 35 position again.

The outer part of each wing 14 is preferably also provided with a notch 16, to facilitate the convenient grasping of the handle part 11 by the thumb and a finger of the hand.

40 This cradle blotter is preferably made from a sheet or strip of fibrous material, which may consist of cardboard, as indicated in Figs. 1 to 6; and it may likewise consist of highly absorbent material, as the usual blotting material, as indicated 45 in Figs. 7 and 8, thereby providing one blotting sheet by the lower section 10.

In the form shown in Figs. 1 to 6, the lower section 10 has several extra blotting layers or blotters 17 provided thereunder, thus providing 50 a longer life and greater usefulness of the device. Said layers 17 may be mounted or secured to section 10 in any convenient manner, as for example by attaching them by adhesive means 18 at their ends onto one another and underneath said section 10. The adhesive means is provided

to a less extent on each layer outwardly than on the preceding layer inward thereof, as best indicated in Figs. 3 and 5, so as to facilitate tearing away each outside layer in succession, while the inward layers are adhered more extensively and remain in position under section 10.

The form of cradle blotter shown in Figs. 7 and 8, like the above described form, comprises the lower section or part 10' and the upper section or part 11' which are integral at one end and have at the other end the lip 12' secured in place. Likewise, the wings 14' extend integral from the sides of upper section 11' and are bendable on lines 15' into engagement with the lower section 10', to retain them in the operative cradle form, and the notches 16' being also provided on said wings.

I claim:

A collapsible cradle blotter consisting of a strip of bendable sheet-like material doubled over and the originally opposite ends having on one end a lip secured with adhesive means to the

other end, thus including a lower cradle part and also an upper handle part thereon which are collapsible one onto the other, said handle part being provided with a pair of score lines and 5 with integral oval-shaped side wings outward thereof that are readily bendable downward and inward on said lines to slant inwardly and bear against the cradle part, whereby to serve as brace means between said two parts and retain them 10 firmly in the operative cradle form, said wings being provided each with a notch to facilitate grasping the handle part with its wings by a finger and the thumb of the hand manipulating this blotter, and said cradle part being provided 15 with a plurality of blotting layers secured at their ends with adhesive means to its nether side, the adhesive means being provided to a less extent on each layer downward than on the preceding layer, to facilitate tearing away each 20 outside layer in succession.

FRIEDA STRAUS.
